UNITED STATES PATENT OFFICE.

HAROLD D. ARNOLD, OF EAST ORANGE, NEW JERSEY, ASSIGNOR TO WESTERN ELECTRIC COMPANY, INCORPORATED, OF NEW YORK, N. Y., A CORPORATION OF NEW YORK.

METHOD OF AND MEANS FOR UTILIZING THERMIONIC CURRENTS.

1,349,252.

Specification of Letters Patent. Patented Aug. 10, 1920.

Application filed March 20, 1916, Serial No. 85,362. Renewed May 16, 1918. Serial No. 235,043.

To all whom it may concern:

Be it known that I, HAROLD DEFOREST ARNOLD, a citizen of the United States, residing at East Orange, in the county of Essex and State of New Jersey, have invented certain new and useful Improvements in Methods of and Means for Utilizing Thermionic Currents, of which the following is a full, clear, concise, and exact description.

10 This invention relates to thermionic amplifiers, and more particularly to circuit arrangements by which the current voltage characteristic is made to have a desired form.

15 An object of the invention is to repeat or amplify electrical impulses substantially without distortion.

This is accomplished by providing a thermionic device wherein the curve which represents the relation between the input voltage and the output current is approximately straight.

20 A further object of the invention is to efficiently transfer electrical impulses, employing a thermionic device.

25 This is accomplished by properly proportioning the internal output circuit impedance with respect to the external output circuit impedance of the thermionic device.

30 This invention will be explained more in detail in connection with the drawings in which Figure 1 represents a thermionic amplifier and its circuit, and Fig. 2 a curve by means of which its operation will be explained. Fig. 3 represents the same thermionic element modified in accordance with this invention, and Fig. 4 a curve which will be used to explain its operation. Fig. 5 represents another modified circuit for the 35 thermionic element of Fig. 1.

40 Referring to Fig. 1, a thermionic vacuum tube is shown containing the filament F, input electrode or grid G, and anode or plate P. In the input circuit of this element is placed a battery C, whose function is to maintain the electrode G at a negative potential with respect to the filament and also to aid in fixing the point on the characteristic at which the amplifier is to be worked. The object of maintaining the grid negative with respect to the filament is to insure that no current shall flow from grid to filament and consequently that the 45 input circuit shall have a very high re-

sistance which shall be independent of the 55 input voltage. The battery B in the output circuit serves to provide the space current from anode P to cathode F, whose variation is utilized to produce the amplified signals. 60

Fig. 2 represents the operation of the amplifier of Fig. 1. In this figure abscissæ E_c represent voltages of the battery C, and ordinates I_b represent values of current in the output circuit. The curve shown is the 65 one which is obtained with the amplifier as used in ordinary operation, and it will be noted that its curvature is sufficiently large to produce distortion or rectification in the signals produced by a variation of input 70 voltage E_c. An object of this invention is to render the characteristic of Fig. 2 approximately straight throughout the operating range while maintaining the ratio of amplification at a sufficiently large value. 75

Fig. 3 shows the amplifier of Fig. 1 connected in a modified circuit. In this figure an additional resistance R has been shown added in the output circuit and the electromotive force of the battery B has been 80 modified in accordance with conditions to be explained later. The electromotive force of the battery C may also need to be modified. The curve in Fig. 4 shows the form of the characteristic when these changes 85 have been made. If in the amplifier of Fig. 1 a resistance R approximately equal to the normal internal resistance of the tube is added in the output circuit, the effect will be to render the characteristic approximately straight, but at the same time to greatly lower the current which flows in the output circuit. To raise this current to its normal operating level, it will be necessary to increase the electromotive force of 95 the battery B, and therefore to increase the space current. It is therefore necessary, in order to secure an approximately straight characteristic and also a desired value of output current, to insert in the output circuit a resistance of the order of magnitude of the internal resistance of the tube and at the same time to vary the electromotive force of battery B in order that the output current may remain fixed at a predetermined 100 value. When these adjustments have been made, operation will take place at an approximately straight part of the character- 105

istic curve and to the left of the current axis in the region of constant input impedance, and at the same time the ratio of amplification is maintained sufficiently high.

- 5 While the resistance has been shown as connected directly in the output circuit of Fig. 3, it is to be understood that the invention is broader than this and that the resistance may be inserted in other ways. It 10 may, for example, be carried into this output circuit by means of a transformer. That is, if as shown in Fig. 5, the resistance R_1 is actually included in the secondary circuit of the output transformer, it will produce an 15 effective resistance in the primary circuits yielding, to all intents and purposes, the same result as if a resistance had been actually placed in this primary circuit. The value of the effective resistance produced in 20 said primary by a given resistance in the secondary circuit will, of course, depend on the ratio of transformation of the transformer.

What is claimed is:

- 25 1. A thermionic amplifier having an input circuit and an output circuit, a source of electromotive force in each of said circuits, and a resistance in said output circuit, the magnitude of said electromotive 30 forces and of said resistance being so related that the output current shall vary approximately linearly as the input voltage over a portion of the characteristic curve 35 suitable for efficient operation of said amplifier.
2. A thermionic amplifier having an input circuit and an output circuit, a source of electromotive force in each of said circuits, and a resistance in said output circuit, said resistance being of such a magnitude 40 that the output current shall vary approximately linearly as the input voltage and said electromotive forces being of such a magnitude as to secure a desired value of 45 said output current.
3. A thermionic amplifier having an input circuit and an output circuit, a source of electromotive force in each of said circuits, and a resistance in said output circuit, said resistance being of such a magnitude 50 that the output current shall vary approximately linearly as the input voltage, said electromotive forces being of such a magnitude as to secure a desired value of 55 said output current, and to maintain a high input circuit impedance.
4. A thermionic amplifier having an input circuit and an output circuit, a source of electromotive force in each of said 60 circuits, and a resistance in said output circuit, said resistance being approximately equal to the normal internal resistance of the tube for the purpose set forth.
5. A thermionic amplifier having an input circuit and an output circuit, a source 65

of electromotive force in each of said circuits and a resistance in said output circuit, said resistance being approximately equal to the normal internal resistance of the tube whereby the output current shall 70 vary approximately linearly as the input voltage, said electromotive forces being of such magnitudes as to secure a desired value of said output current, and to maintain a high input circuit impedance.

6. A thermionic device having an input circuit and an output circuit, a resistance in said output circuit, said resistance being of the same order of magnitude as the internal impedance of the said device.

7. A thermionic device having an input circuit and an output circuit, the resistance of said output circuit external to said device being of the same order of magnitude as the internal impedance of the said device.

8. A thermionic device having an input circuit and an output circuit, a resistance in said output circuit external to said device, said resistance being of the same magnitude 80 as the internal impedance of the said device.

9. A thermionic repeater having cathode, anode and control electrodes, means for supplying current between said cathode and anode, means connected to said cathode and control electrode for impressing thereon alternating currents to be repeated, and an output circuit connected to said cathode and anode, said output circuit having an impedance such that said alternating currents are repeated substantially without distortion.

10. A thermionic device wherein the curve which represents the relation between 105 input voltage and output current is approximately straight.

11. A thermionic repeater having an input circuit and an output circuit, said output circuit external to said repeater having 110 an impedance such that the curve which represents the relation between input voltage and output current is approximately straight.

12. A thermionic repeater having an input and an output circuit, said output circuit external to said repeater having an impedance of the same order of magnitude as the internal impedance of the said repeater.

13. A thermionic repeater having an input and an output circuit, said output circuit external to said repeater having a resistance at least as large as the internal impedance of the said repeater.

14. A thermionic repeater having an input and an output circuit, said output circuit external to said repeater having an impedance at least as large as the internal impedance of the said repeater.

15. A thermionic repeater having an in-

- put circuit and an output circuit, a source of electromotive force in each of said circuits, said output circuit having an impedance, the magnitude of said electromotive forces and said impedance being such as to cause the output current to vary approximately linearly as the input voltage over a portion of the characteristic curve suitable for efficient operation of the said repeater.
16. A thermionic device having an input circuit and an output circuit, means for maintaining substantially an infinite impedance for said input circuit, the curve which represents the relation between the input voltage and output current of said device being approximately straight.
17. A thermionic amplifier having cathode, anode and control electrodes, means for supplying between said cathode and anode a current the variation of which with voltage is substantially constant, means connected to said cathode and control electrode for impressing thereon alternating currents to vary the discharge between cathode and anode within a range corresponding to that part of the volt-ampere characteristic of said amplifier that exhibits no substantial departure from a straight line, and an output circuit connected to said cathode and anode.
18. The method wherein is employed a thermionic device comprising a hot cathode and a control electrode for amplifying a variable electric current without distortion which comprises producing from said cathode an electron discharge the variation of which with voltage is substantially constant, and applying the input current to produce corresponding electromotive forces across said cathode and said control electrode, thereby varying said discharge within the range for which the ratio of current increment to voltage increment remains substantially constant.
19. The method wherein is employed a thermionic device comprising a hot cathode and a grid for amplifying a variable electric current without distortion which comprises producing from said cathode an electron discharge the variation of which with voltage is substantially constant, substantially infinitely impeding the input current and applying the input current to produce corresponding electromotive forces across said cathode and said grid, thereby varying said discharge within the range for which the ratio of current increment to voltage increment remains substantially constant.

In witness whereof I hereunto subscribe my name this 18th day of March, A. D. 1916.

HAROLD D. ARNOLD.
